CLAIM

I claim the ornamental design for a jewellery article, as shown and described.

DESCRIPTION

FIG. 1 is a front, top, and right side perspective view of a jewellery article showing my new design;

FIG. 2 is a front elevational view thereof, the rear being a mirror image;

FIG. 3 is a top plan view thereof;

FIG. 4 is a bottom plan view thereof;

FIG. 5 is a right side elevational view thereof; and,

FIG. 6 is a left side elevational view.

The features shown in broken lines in the drawings form no part of the claimed design.

1 Claim, 6 Drawing Sheets(56)
